UNITED STATES PATENT OFFICE.

JOHN B. GRUELLE, OF NORWALK, CONNECTICUT.

DESIGN FOR A TOY ANIMAL.

58,314.

Specification for Design.

Patented July 12, 1921.

Application filed March 16, 1920. Serial No. 366,427. Term of patent 14 years.

To all whom it may concern:

Be it known that I, JOHN B. GRUELLE, a citizen of the United States, and a resident of Norwalk, county of Fairfield, State of Connecticut, have invented a new, original, and ornamental Design for a Toy Animal, of which the following is a specification, reference being had to the accompanying drawing, forming a part thereof.

Fig. 2 is a side view of the same.

I claim:

The ornamental design for a toy animal as shown.

In testimony whereof, I have signed my name to this specification this 12th day of March.

JOHN B. GRUELLE.
